UNITED STATES PATENT OFFICE.

GEORGE M. HUBINGER, OF MILWAUKEE, WISCONSIN.

TOWEL-DISPENSING CABINET.

Application filed April 14, 1924. Serial No. 706,510.

To all whom it may concern:

Be it known that I, GEORGE M. HUBINGER, a citizen of the United States, and resident of Milwaukee, in the county of Milwaukee, and State of Wisconsin, have invented certain new and useful Improvements in Towel-Dispensing Cabinets; and I do hereby declare that the following is a full, clear, and exact description thereof.

10 This invention relates to towel dispensing cabinets.

Objects of this invention are to provide a towel dispensing cabinet which is so constructed that the towels are retained in a sanitary condition until they are used, which is provided with means for supporting the towels, and independent means for holding the towels loosely in their initial position, and which is so constructed that 20 the used towels are securely retained against unauthorized removal and are stored in the lower portion of the cabinet in an automatic manner.

A further important object of this invention is the provision of means for deflecting any fumes or vapors that may rise from the used towels and for keeping these gases or other soiling agencies from contacting with the clean towels.

30 Further objects are to provide a towel dispensing cabinet which is so constructed that the necessity for doors is wholly avoided and yet in which the towels are, as stated, retained against unauthorized removal.

35 An embodiment of the invention is shown in the accompanying drawings in which:—

Figure 1 is a vertical sectional elevation through the cabinet, such view being taken on the line 1—1 of Figure 2.

40 Figure 2 is a horizontal sectional view on the line 2—2 of Figure 1, the towels being omitted in this view for the sake of clearness.

The device comprises a cabinet having a 45 straight back portion 1, a bottom 2, a top 3 and a forwardly spaced front wall 4 extending a portion of the height of the cabinet. The cabinet may conveniently be supported by legs, as shown, and is also preferably provided with a downturned ledge or flange 5 extending from the lower portion of the top 3 to hide the upper portion of the supporting device, and to provide a finished appearance. An upwardly and forwardly slanting partition 6 extends from an intermediate portion of the back to a point ap-

proximately level with the upper portion of the front wall 4. This partition is provided with upturned flanges 7, as illustrated in Figure 1.

It is preferable to form the front edge of the sides 8 of the cabinet with an inwardly offset portion 9 aligning with the depending flange 5, as shown in Figure 1, and to extend these side walls outwardly until they engage the side posts of the front wall 4, as shown. It is to be noted also that the cabinet is preferably provided with the posts 10 which form a continuation of the front legs and 70 also with posts or strengthening members 11 which form continuations of the rear legs and extend upwardly throughout the entire height of the cabinet.

The towels 12 are provided with gromets 75 or eyes which are loosely received upon a supporting bar 13, such bar being removably retained in any suitable form of locking or clamping socket member 13'. The bar is preferably provided with an enlarged flange 80 14 at its rear end, as illustrated in Figure 1.

In order to hold the towels in their initial position, and to loosely retain them, an independent U-shaped strap or bar 15 is secured at spaced points to the back wall 1 of the 85 cabinet, as shown in Figures 1 and 2. This looped member is adapted to engage or surround the central portion of the towels, as shown, and to hold them in a neat and attractive manner.

It is to be noted that the supporting bar 13 extends outwardly beyond the forward edge of the partition 6. A chain or similar flexible member 16 is secured to the forward edge of this bar and depends in a free manner into the lower compartment of the cabinet and free of engagement with either the partition 6 or the front wall 4 thereof. The lower end of the chain 16 is provided with an enlarged lock or retaining member 17 of 100 a well known type to prevent unauthorized removal of the towels.

It is to be distinctly noted that no retaining means whatsoever are carried by the bar 13 and consequently a person intending 105 using the towels is not compelled to manipulate any apparatus whatsoever with his wet hands. He is merely required to grasp a towel and draw it free of the embracing loop 15, thus requiring him to place his wet hands 110 solely upon the towels and avoiding any contact with other portions of the apparatus or

any manipulation of the towels. In other words, when it is desired to use a towel, it is merely necessary to grasp such towel and draw it forwardly into a position to be freely used.

It will thus be seen that a towel dispensing cabinet has been provided which is sanitary, which is of attractive appearance, which may be most readily constructed, and which is so formed that no manipulation either of the towel or of locking means is required by the user.

It will be further seen that the partition deflects any vapors that may arise from the used towels upwardly and outwardly from the cabinet, and prevent such vapors from contacting with, contaminating, or rendering the fresh towels odoriferous.

It is to be noted that the upwardly extending flange 7 of the partition also acts as a retaining means for the unused or fresh towels, although it is preferable to provide the bar 15. In other words, it is preferable to have a distinct and effective retaining means intermediate the length of the towels.

It will thus be seen that a towel dispensing cabinet has been provided which is of attractive appearance, of simple construction, and of an efficient nature.

Although the invention has been described in considerable detail, it is to be understood that the invention may be variously embodied and is, therefore, to be limited only as claimed.

I claim:

1. A towel dispensing cabinet comprising an upright body portion having a back extending the complete length of the device, a forwardly and upwardly extending partition carried by said back and projecting there-

from, a part length front wall extending upwardly from the front portion of the cabinet and defining a lower compartment, a bar carried by said back adjacent its upper portion and projecting forwardly beyond the forward edge of said partition, a chain carried by the forward end of said bar and loosely hanging downwardly and extending into the lower compartment and provided with an enlarged lower end, said bar being adapted to receive eyeletted towels, a U-shaped bar secured to said back at a point spaced below said supporting bar and adapted to surround an intermediate portion of said towels.

2. A towel dispensing cabinet comprising a body portion having an upper compartment opening forwardly, and a lower compartment opening upwardly, a partition dividing said body portion and located between said compartments, said lower compartment having its front wall spaced outwardly from the back a greater distance than said partition, a supporting rod carried in the upper compartment and extending forwardly beyond said partition, a chain carried by the forward end of said rod and hanging downwardly into said lower compartment and provided with an enlarged lower end, a U-shaped retaining bar carried within said upper compartment and located below said first mentioned bar, whereby eyeletted towels may be supported by said first mentioned bar and may be surrounded intermediate their ends by said U-shaped bar.

In testimony that I claim the foregoing I have hereunto set my hand at Milwaukee, in the county of Milwaukee and State of Wisconsin.

GEO. M. HUBINGER.
